(Cl. D85—2)

To all whom it may concern:

Be it known that I, Monroe B. Toklas, a citizen of the United States of America, residing in New York city, county of New York, and State of New York, have invented a new, original, and ornamental Design for a Cigarette Case or Similar Article, of which the following is a specification, reference being had to the accompanying drawing, forming part thereof, wherein, rette case or similar article showing my new design.

I claim:

The ornamental design for a cigarette case or similar article, substantially as shown.

MONROE B. TOKLAS.
